HYDRAZINE SULPHONATE

Arthur Zitscher and Wilhelm Seidenfaden, Offenbach-on-the-Main, Germany, assignors to General Aniline Works, Inc., New York, N. Y., a corporation of Delaware

No Drawing. Application December 29, 1932,
Serial No. 649,446. In Germany January 12,
1932

4 Claims. (Cl. 260—124)

The present invention relates to new hydrazine-sulphonates, more particularly it relates to compounds corresponding to the following probable general formula:

10 wherein Y stands for alkyl, alkoxy or halogen.

These compounds are produced by acting with a reducing agent on the corresponding 2,5-disubstituted 4-acylamino-benzene-1-diazo-sulphonic acids.

15 They are of a great value for the production of azo-dyestuffs. For this purpose, they are advantageously first mixed with combining components containing a hydroxy- or an o-alkali metal group, whereof the adjacent position is capable of attaching an aryl azo group, provided that neither of the dyestuff components contains a group producing solubility in water. The compositions of matter, thus produced, are then brought onto the fibers in the presence of an alkali and the goods, thus treated, are thereafter subjected to a steaming operation.

20 As combining components of the aforesaid kind may be named: 2-hydroxynaphthalene, its nuclear substitution products as, for instance, aroylamino - hydroxynaphthalenes, (2 - hydroxynaphthalene-3-carbonyl) - amino-aryls (as described in U. S. Patents No. 1,101,111 and No. 1,140,747), (6-halogen- or 6-arylamino-2-hydroxy-naphthalene-3-carbonyl) - amino-aryls (see German Patent No. 396,519 and British Patent No. 330,349), derivatives of 1-hydroxy-naphthalene-4-carboxylic acid (see U. S. Patent No. 1,453,660), as, for instance, 1-hydroxy-naphthalene - 4 - phenyl-ke-25 tone; compounds containing an acidic methylene group capable of being combined with diazo-compounds, as, for instance, pyrazolones and derivatives of β -ketonaldehyde, for instance, aceto-acetyl-amino-aryls and di-(aceto-acetyl-amino) - aryls (see U. S. Patents No. 1,594,864, No. 1,594,866, No. 1,594,867, No. 1,580,709, No. 1,634,090), di-hydroxy-quinolines (see U. S. Patents No. 1,820,039, No. 1,846,073 and No. 1,846,074, British Patent No. 332,940), (2-hydroxy-carbazole-3-carbonyl) - amino-aryls, (2 - hydroxy - benzo - carbazole-3-carbonyl) - amino-aryls, (2 - hydroxy - an-thracene-3-carbonyl) - amino-aryls.

30 The hydrazine-sulphonate and the coupling component, or an alkali metal salt of the latter,

may be ground together and this mixture may be applied in an alkaline medium to the fiber. The dyeing preparations yield under these conditions, by steaming only, insoluble azo-dyestuffs on the fiber.

35 Such application to the fiber may consist in dyeing according to the one-bath method, or in printing; the dye-bath or the printing paste, or even the dyeing preparations themselves in powder form, are advantageously mixed with the usual dyeing or printing assistants having wetting, emulsifying or solvent properties, or also with the additional agents customarily used in nitrosamine-printing colors, such as, for example, chromate.

The following examples serve to illustrate the invention, but they are not intended to limit it thereto, the parts being by weight:

(1) 225 parts of the sodium salt of 4-benzoylamino - 2.5 - dimethoxybenzene-1-diazo - sul- 20 phonic acid of 87.05% strength are suspended in 3000 parts of acetic acid of 3% strength, the whole is heated to 60° C. to 70° C. and at this temperature 150 parts of zinc dust are slowly introduced. When the mass has become dissolved 25 and decolorized, it is rendered alkaline by means of sodium carbonate, filtered by suction while hot, sodium chloride is added and the product worked up as usual. There are thus obtained 385 parts of a feebly yellow press cake of the sodium salt 30 of 4-benzoylamino-2.5-dimethoxybenzene-1-hy-drazine-sulphonic acid containing 58.35% of the pure substance.

35 It corresponds to the following formula:

(2) 394 parts of the sodium salt of 4-benzoylamino-2-chloro-5 - methoxybenzene-1-diazo-sulphonic acid are suspended in a solution of 100 parts of calcined sodium carbonate in 4000 parts of water, 125 parts of sodium hydrosulphite are 40 added thereto and the whole is heated in the course of $\frac{1}{2}$ hour to 60° C. to 65° C. This temperature is maintained until the mass has become decolorized, indicating complete reduction. 45 Thereupon, the whole is heated to 85° C. to 90° C., filtered by suction, sodium chloride is added to the filtrate and the product is worked up as usual. There are obtained 1222 parts of a nearly colorless paste of the sodium salt of 4-benzoyl- 50

55

amino-2-chloro-5-methoxybenzene-1-hydrazine sulphonic acid containing 19.36% of the pure substance.

It corresponds to the following formula:

5

10

In an analogous manner, the corresponding hydrazine sulphones are obtained by starting from other 2,5-disubstituted-4-acylamino-benzene-1-diazosulphonic acids of the above mentioned kind, as, for instance,

15

4-benzoylamino-2-methoxy-5-methylbenzene-1-diazosulphonic acid,

4-benzoylamino-2,5-diethoxybenzene-1-diazosulphonic acid,

20

4-acetylamino-2,5-dimethoxybenzene-1-diazosulphonic acid,

4-acetylamino-2,5-dimethylbenzene-1-diazosulphonic acid,

4-(phenoxy-acetyl-amino)-2,5-dimethoxybenzene-1-diazosulphonic acid,

25

4-(4'-methylbenzene-1'-sulphonylamino)-2,5-dimethoxybenzene-1-diazosulphonic acid,

4-benzoylamino-2,5-dimethylbenzene-1-diazosulphonic acid,

30

4-benzoylamino-2-methyl-5-chlorobenzene-1-diazosulphonic acid,

4-(α - or β -naphthoylamino)-2-methoxy-5-methylbenzene-1-diazosulphonic acid,

4-benzoylamino-2-chloro-5-methylbenzene-1-diazosulphonic acid,

35

4-(3'-methoxy-naphthalene-2'-carbonylamino)-2,5-dimethoxybenzene-1-diazosulphonic acid,

4-(2'-chlorobenzoylamino)-2,5-diethoxybenzene-1-diazosulphonic acid,

40

4-benzoylamino-6,2,6-Bis(2-hydroxy-4-diazosulphonic acid).

4-(4'-methoxybenzoylamino)-2,2-dimethoxy-4-diazosulphonic acid,

4-benzoylamino-6-2,2-dimethoxy-4-diazosulphonic acid,

45

4-(4-methoxy-2,2-dimethoxybenzene-1-diazosulphonic acid).

50

4-benzoylamino-6-2,2-dimethoxy-4-diazosulphonic acid,

55

4-(4-methoxy-2,2-dimethoxybenzene-1-diazosulphonic acid).

60

4-benzoylamino-6-2,2-dimethoxy-4-diazosulphonic acid,

65

4-(4-methoxy-2,2-dimethoxybenzene-1-diazosulphonic acid).

70

4-benzoylamino-6-2,2-dimethoxy-4-diazosulphonic acid,

75

4-(4-methoxy-2,2-dimethoxybenzene-1-diazosulphonic acid).

80

4-benzoylamino-6-2,2-dimethoxy-4-diazosulphonic acid,

85

4-(4-methoxy-2,2-dimethoxybenzene-1-diazosulphonic acid).

90

4-benzoylamino-6-2,2-dimethoxy-4-diazosulphonic acid,

95

4-(4-methoxy-2,2-dimethoxybenzene-1-diazosulphonic acid).

100

4-benzoylamino-6-2,2-dimethoxy-4-diazosulphonic acid,

105

4-(4-methoxy-2,2-dimethoxybenzene-1-diazosulphonic acid).

110

4-benzoylamino-6-2,2-dimethoxy-4-diazosulphonic acid,

115

4-(4-methoxy-2,2-dimethoxybenzene-1-diazosulphonic acid).

120

4-benzoylamino-6-2,2-dimethoxy-4-diazosulphonic acid,

125

4-(4-methoxy-2,2-dimethoxybenzene-1-diazosulphonic acid).

130

4-benzoylamino-6-2,2-dimethoxy-4-diazosulphonic acid,

135

4-(4-methoxy-2,2-dimethoxybenzene-1-diazosulphonic acid).

140

4-benzoylamino-6-2,2-dimethoxy-4-diazosulphonic acid,

145

4-(4-methoxy-2,2-dimethoxybenzene-1-diazosulphonic acid).

150

4-benzoylamino-6-2,2-dimethoxy-4-diazosulphonic acid,

155

4-(4-methoxy-2,2-dimethoxybenzene-1-diazosulphonic acid).

Caustic soda solution of 34° Bé.	30
Water	273
Starch tragacanth-thickening	500
Sodium chromate solution (1:4)	20

5

is printed on the material; the material is then dried, steamed for 10 minutes in a Mather-Platt apparatus; rinsed hot, soaped and rinsed again.

A violet print is thus obtained.

(5) 60 parts of the sodium salt of 4-benzoyl-amino-2,5-dimethoxybenzene-1-hydrazine-sulphonic acid of 58.35% strength, obtainable as described in Example 1, 10 parts of anhydrous sodium acetate and 30 parts of 2-hydroxyanthracene-3'-carbonyl-(1-amino-2-methylbenzene) are ground to form a homogeneous powder. There are obtained 100 parts of dyestuff preparation.

A printing paste which contains:

	Parts
The above dyestuff preparation	50
Thiodiglycol	20
Caustic soda solution of 34° Bé.	35
Water	375
Neutral starch tragacanth-thickening	500
Sodium chromate solution (1:4)	20

is printed on the material and the goods are treated as indicated in Example 4.

A bluish-green print is obtained.

By using, instead of 2'-hydroxy-anthracene-3'-carbonyl-(1-amino-2-methylbenzene), 3-benzoylamino-2-hydroxynaphthalene, a violet print is obtained.

(6) A printing paste which contains:

	Parts
2',3'-hydroxynaphthoyl-(1-amino-2-methoxy-4-chlorobenzene)	15
The sodium salt of 4-benzoylamino-2,5-dimethoxybenzene-1-hydrazine-sulphonic acid of 58.35% strength	30
Thiodiglycol	20
Caustic soda solution of 34° Bé.	35
Water	350
Starch tragacanth-thickening	500
Sodium chromate solution (1:4)	20

is printed on the material and the goods are treated as indicated in Example 4.

A bluish-violet print is thus obtained.

(7) 100 parts of the sodium salt of 4-benzoyl-amino-2,5-dimethoxybenzene-1-hydrazine-sulphonic acid of 58.35% strength, 12.5 parts of sodium acetate and 50 parts of 2-hydroxyanthracene-3'-carbonyl-(1-amino-2-methylbenzene) are ground to form a homogeneous mixture. 17.5 parts of a homologous dyestuff (1:4) are added to the mixture. 100 parts of a homologous dyestuff (1:4) are added to the mixture. 100 parts of a homologous dyestuff (1:4) are added to the mixture.

A printing paste containing:

	Parts
The above dyestuff preparation	100
Thiodiglycol	50
Caustic soda solution of 34° Bé.	100
Water	100
Starch tragacanth-thickening	100
Sodium chromate solution (1:4)	20

is printed on the material and the goods are treated as indicated in Example 4.

A bluish-violet print is thus obtained.

By using, instead of 2-hydroxyanthracene-3'-carbonyl-(1-amino-2-methylbenzene), 3-benzoylamino-2-hydroxynaphthalene, a violet print is obtained. 100 parts of a homologous dyestuff (1:4) are added to the mixture and the mixture is then ground to form a homogeneous mixture. 100 parts of a homologous dyestuff (1:4) are added to the mixture and the mixture is then ground to form a homogeneous mixture.

5

The following table indicates the shades of a yellowish to brownish powders and are valuable series of other dyeings or prints obtained in an intermediates for the production of azo dyestuffs.

5	Sodium salt of 4-benzoyl-amino-2,5-diethoxybenzene-1-hydrazine sulphonic acid.	2-hydroxynaphthalene.....	Brownish violet.	5
	Do.....	3-methyl-1-phenyl-5-pyrazolone.....	Brownish-orange.	
	Do.....	1-hydroxynaphthalene-4-phenylketone.....	Violet.	
	Do.....	2'-hydroxy-carbazole-3'-carbonyl-(1-amino-4-chlorobenzene)	Do.	
	Do.....	3-benzoylamino-2-hydroxynaphthalene.....	Do.	
	Do.....	4,4'-di-(acetoacetyl-amino)-3,3'-dimethyl-diphenyl.....	Yellowish-orange.	
	Do.....	2',3'-hydroxynaphthoyl-(1-amino-2-methoxy-benzene).....	Reddish-blue.	
10	Sodium salt of 4-acetyl-amino-2,5-dimethoxy-benzene-1-hydrazine sulphonic acid.	do.....	Do.	
	Do.....	4,4'-di-(acetoacetyl-amino)-3,3'-dimethyl-diphenyl.....	Yellowish-orange.	10
	Do.....	do.....	Yellow.

	Sodium salt of 4-(4'-methylbenzene-1'-sulphonyl-amino)-2,5-dimethoxy-benzene-1-hydrazine sulphonic acid.	2',3'-hydroxynaphthoyl-aminobenzene.....	Reddish-violet.	15

analogous manner:

We claim:

1. The hydrazine sulphonates corresponding to the general formula:

wherein Z means an acyl radical of the lower aliphatic series or of the aromatic isocyclic series and Y stands for alkyl, alkoxy or halogen, which compounds represent when dry yellowish to brownish powders and are valuable intermediates for the production of azo dyestuffs.

2. The hydrazine sulphonates corresponding to the general formula:

40 wherein R represents a radical of the aromatic isocyclic series and Y stands for alkyl, alkoxy or halogen, which compounds represent when dry

3. The hydrazine sulphonates corresponding to the general formula:

wherein the benzene nucleus I may be substituted by alkyl, alkoxy or halogen and Y means alkyl, alkoxy or halogen, which compounds represent when dry yellowish to brownish powders and are valuable intermediates for the production of azo dyestuffs.

4. The 4-benzoylamino - 2,5 - dimethoxy - benzene-1-hydrazine-sulphonate of the formula:

which compound represents a feebly yellow powder and is a valuable intermediate for the production of azo dyestuffs.

ARTHUR ZITSCHER.
WILHELM SEIDENFADEN.
